(57) **CLAIM**

The ornamental design for a pulse oximeter probe as shown and described.

DESCRIPTION

FIG. 1 is a front perspective view of a pulse oximeter probe showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof, and the broken lines in FIG. 7 are for the purpose of illustrating portions of the pulse oximeter probe and form no part of the claimed design; and, FIG. 8 is a perspective view showing the pulse oximeter probe in a design configuration, in its environment of use, with the cable connected.

The broken lines showing the cable in FIG. 8 are for the purpose of illustrating environmental structure and form no part of the claimed design.
